UNITED STATES PATENT OFFICE.

ALFRED BODE AND KARL BÖTTCHER, OF BENRATH, NEAR DUSSELDORF, GERMANY.

FLOATING CRANE.

No. 927,934.

Specification of Letters Patent.

Patented July 13, 1909.

Application filed February 18, 1907. Serial No. 358,033.

To all whom it may concern:

Be it known that we, ALFRED BODE and KARL BÖTTCHER, subjects of the King of Prussia, and residents of Benrath, near Dusseldorf, in the Province of the Rhine, German Empire, have invented certain new and useful Improvements in Floating Cranes, of which the following is an exact specification.

- In cranes with beams movable in a vertical plane it is well known to connect the beams with a weight in such a manner that the weight tends to pull the beam up, whereby the winding up device is relieved to a certain extent.
- The present invention relates to floating cranes, in which, as is well known, counter weights are used to partially balance the tilting forces that come in action on one side in cranes used on pontoons.
- The object of the present invention is to simultaneously use these balancing counter-weights on floating cranes with jibs or beams to relieve the winding-up device, which serves for pulling up the beam on the floating cranes.

In the accompanying drawing one embodiment of the invention is illustrated.

Upon a pontoon *a* the rotatory crane is shown, in which the rotary column structure *b* carries a lifting member in the form of a beam or jib *c*, the latter swinging in a vertical direction. The drawing-up of the beam *c* is effected by means of the screw-spindle *d* which passes through a swinging screw-nut *c'* mounted at the edge opposite to the turning axis of the beam. The screw-spindle is rotated by means of a pair of bevel-wheels *g h*, the wheel *g* being arranged at the lower end of the screw spindle *d* and the wheel *h* on the upper rear edge of the column *b*.

i is a gear wheel rigidly connected with the bevel *h*. The bevel wheel *i* is operated by means of the bevel wheels *k m*, and the shaft *n*, which is driven by a suitable motor (not shown). According to the turning direction of the shaft the beam is either drawn up or lowered. The counter-weight *e* is suspended on the rear side of the column *b* in such a manner, that the carrying rope, one end of which is attached to the upper rear edge of the beam, passes over a guide roller *c*. In the embodiment shown in the

drawing the rope is conducted over another roller *f*, secured to the weight and the other end of the rope is attached to the column 55 structure at *b*². This pulley-block like arrangement may of course be departed from and the weight may if desired be directly secured to the beam. In such case the weight cannot have such a low position as is the 60 case when the pulley-block connection is employed.

During the drawing-up or derricking motion of the jib the momentum resulting from the combined actions of the jib load and 65 balance weight will on one side of the center of rotation decrease to zero and, if the drawing up is continued, increase again on the other side. In the latter case the shaft *d* will be subject to pressure. This is in most 70 cases disadvantageous and in order to limit this action of the balance weight as much as required, we provide, on the lower part of the column *b*, a support *g* which receives the balance-weight *e* at a suitable moment and 75 stops its action.

Instead of arranging the upper part of the crane so as to be rotatable in a horizontal plane as is shown in the drawing, such rotation may be dispensed with, the upper part 80 of the crane being rigidly connected with the floating pontoon.

Having now particularly described and ascertained the nature of our said invention, and in what manner the same is to be performed, we declare that what we claim is:

1. The combination with a pontoon and a crane carried thereby having a vertically movable lifting jib, of means acting as ballast for said jib to maintain the stability of 90 the pontoon, and operative also to tend to raise the said jib.

2. The combination with a pontoon and a crane carried thereby having a vertically movable lifting jib, of a weight having connection with said jib and so located with respect thereto as to act as ballast for the jib to maintain the stability of the pontoon, and to be operative also to tend to raise said jib.

3. The combination with a pontoon and a rotatable crane carried thereby having a vertically movable lifting jib, of means rotating with said crane acting as ballast for

- said jib to maintain the stability of the pontoon, and operative also to tend to raise said jib.
4. The combination with a pontoon and a crane carried thereby having a vertically movable lifting jib, of means acting as ballast for said jib to maintain the stability of the pontoon, and operative also to tend to raise the said jib, and means adapted to 10 arrest the action of said means tending to raise the jib.
5. The combination with a pontoon and a crane carried thereby having a vertically movable lifting jib, of means acting continuously as ballast for said jib to maintain the stability of the pontoon, and operative temporarily only to tend to raise said jib.
6. In combination with a pontoon and a rotatable crane carried thereby having a vertically movable lifting jib, of means rotating with said crane and acting continuously as ballast for said jib to maintain the stability of the pontoon, and operative temporarily only to tend to raise said jib.
7. The combination with a pontoon and a crane carried thereby having a vertically movable lifting jib, of means acting continuously as ballast for the said jib to maintain the stability of the pontoon, and operative 25 to tend to lift the jib during a portion only of the vertical movement of said jib.
8. The combination with a pontoon and a crane carried thereby having a vertically movable lifting jib, of means acting continuously as ballast for said jib to maintain the stability of the pontoon, and operative to tend to raise said jib only to a point of the vertical movement of the said jib beyond the point at which the combined moment of jib 30 and ballast acts upon the ballast side of the axis of rotation of said jib.
9. The combination with a pontoon and a crane carried thereby having a vertically movable lifting jib and means adapted to move said jib, of means acting as ballast for said jib to maintain the stability of the pontoon, and operative also to tend to raise said jib.
10. The combination with a pontoon and a crane carried thereby having a vertically movable lifting jib and a rotatable spindle adapted to move said jib, of means acting as ballast for said jib to maintain the stability of the pontoon, and operative also to tend to raise said jib.
11. The combination with a pontoon and a rotatable crane carried thereby having a vertically movable lifting jib and a rotatable spindle adapted to move said jib, of means rotating with the said crane acting as ballast for said jib to maintain the stability of the pontoon, and operative also to tend to raise the said jib.
12. The combination with a pontoon and a crane carried thereby having a vertically movable lifting jib and a rotatable spindle adapted to move said jib, of means acting continuously as ballast for said jib to maintain the stability of the pontoon, and operative temporarily only to tend to raise said jib. 65
13. The combination with a pontoon and a crane carried thereby having a vertically movable lifting jib and a rotatable spindle adapted to move said jib, of a weight having connection with said jib and so located with respect thereto as to act as ballast for same to maintain the stability of the pontoon, and to be operative also to tend to raise said jib, and means adapted to arrest the action of 70 said weight tending to raise said jib. 75
14. The combination with a pontoon and a crane carried thereby having a vertically movable lifting jib and a rotatable spindle adapted to move said jib, of means acting continuously as ballast for said jib to maintain the stability of the pontoon, and operative only to tend to raise said jib to a point of the vertical movement of said jib at which the combined moment of the jib and the ballast causes undue compression on said 80 spindle. 85
15. The combination with a pontoon and a crane carried thereby comprising a supporting structure, a vertically movable lifting jib carried thereby, and means adapted to move said jib, of means acting as ballast for said jib to maintain the stability of the pontoon, and operative also to tend to raise 90 said jib. 95
16. The combination with a pontoon and a crane carried thereby comprising a rotatable supporting structure, a vertically movable jib carried thereby, and means adapted to move said jib, of means rotating with said crane and acting as ballast for said jib to maintain the stability of the pontoon, and operative also to tend to raise said jib. 100
17. The combination with a pontoon and a crane carried thereby comprising a supporting structure, a vertically movable lifting jib carried thereby, and a rotatable spindle adapted to move said jib, of a weight having connection with said jib and so located with respect thereto as to act as ballast for said jib to maintain the stability of the pontoon, and to be operative also to tend to raise said jib, and means adapted to arrest the action of said weight tending to raise 105 said jib. 110
18. The combination with a pontoon and a crane carried thereby comprising a supporting structure, a vertically movable lifting jib carried thereby, and a rotatable spindle adapted to move said jib, of a weight having connection with said jib and so located with respect thereto as to act as ballast for said jib to maintain the stability of the pontoon, and to be operative also to tend to raise said jib, and means adapted to arrest the action of said weight tending to raise 115 said jib. 120
19. The combination with a pontoon and a crane carried thereby comprising a supporting structure, a vertically movable lifting jib carried thereby, and a rotatable spindle adapted to move said jib, of a weight having connection with said jib and so located with respect thereto as to act as ballast for said jib to maintain the stability of the pontoon, and to be operative also to tend to raise said jib, and means adapted to arrest the action of said weight tending to raise 125 said jib. 125

cated with respect thereto as to act as ballast for the jib to maintain the stability of the pontoon, and to be operative also to tend to raise the said jib, and means adapted to arrest the action of said weight at a point of the vertical movement of said jib at which the combined moment of the jib and ballast causes undue compression on said spindle.

The foregoing specification signed at Dusseldorf Germany this seventh day of February 10 1907.
